DESIGN FOR AN AIRPLANE

Robert J. Woods, Grand Island, N. Y., assignor to
Bell Aircraft Corporation, Buffalo, N. Y., a cor-
poration of New York

Application February 17, 1939, Serial No. 83,066

Term of patent 14 years

To all whom it may concern:

Be it known that I, Robert J. Woods, a citizen
of the United States, residing at Grand Island,
county of Erie, State of New York, have invented
a new, original, and ornamental Design for an
Airplane, of which the following is a specifica-
tion, reference being had to the accompanying
drawing, forming a part thereof.

Figure 1 is a top plan view of an airplane show-
ing my novel design.

Figure 2 is a front end view of the airplane
shown in Figure 1.

Figure 3 is a side elevational view of the air-
plane shown in Figure 1.

I claim:

The ornamental design for an airplane, as
shown.

ROBERT J. WOODS.
